UNITED STATES PATENT OFFICE.

OSCAR HAMMERSTEIN, OF NEW YORK, N. Y.

CIGAR-MAKING MACHINE.

967,187.

Specification of Letters Patent. Patented Aug. 16, 1910.

Application filed March 13, 1902. Serial No. 98,069.

To all whom it may concern:

Be it known that I, OSCAR HAMMERSTEIN, a citizen of the United States, residing in the borough of Manhattan, city, county, and 5 State of New York, have invented certain new and useful Improvements in Cigar-Making Machines, of which the following is a specification.

My invention relates to cigar making machines and has for its object to produce a machine which shall as nearly as possible imitate hand labor, and which at the same time shall be so simple in construction that it may be readily operated by an inexperienced person.

I am aware that cigar machines have heretofore been devised, but such machines have for the most part required skilled labor to operate them, and consequently the cost 20 of operation was considerable. I have found that by imitating hand labor closely a successful cigar machine can be produced which can be operated by unskilled labor.

In the accompanying drawing I have 25 shown one machine in which my invention is embodied, it being understood that other forms of machine than that shown are equally within my invention.

In this drawing, Figure I is a plan view 30 of the machine; Fig. II is a transverse section thereof on line A—A of Fig. I; Fig. III is a side or end elevation of the machine looking from the left of Fig. I; Fig. IV is a detail sectional view showing the mounting and transmission gear of the rollers; Fig. V is a detail view of a modified form of 35 rolling table; Fig. VI is a section on line B—B of Fig. V; Fig. VII is a section on line C—C of Fig. V.

40 The principal parts of the machine illustrated in the drawing are a rolling table designated 1 in the drawing and a plurality of rollers coöperating therewith. These rollers are designated 2 in the drawing and 45 are so mounted with respect to the rolling table that a cigar bunch *a* held between the rollers will bear upon the rolling table so that the rolling table, which is given a motion of translation by suitable means, one 50 of which will presently be described, will serve the purpose or function of a rolling table, and will also take the place of another roller; the wrapper being peeled from the rolling table in precisely the same manner 55 as the wrapper is peeled from the rolling

table by the hand operator, and not drawn laterally therefrom.

The rolling table and rollers may receive motion in any suitable manner, the essential condition being that the rollers shall receive 60 a rotary motion to rotate the bunch, and motion of translation shall take place either by the rollers or the rolling table, so as to produce a relative movement between the rollers and rolling table, such as will cause the 65 wrapper to be peeled from the rolling table, rather than to be drawn laterally therefrom.

In the present instance I have shown the rolling table as receiving a movement of translation in two directions at angles to 70 each other. This motion may be produced in any suitable or desired manner. One mechanism for moving the table is shown in the drawing. In this drawing the rolling table 1 is shown as provided with a wrapper 75 support or suction box 3 having an air-pipe shown diagrammatically at 4 leading therefrom. The wrapper support is also provided with a curved or beveled breast adapted for the formation of the head of the 80 cigar. The wrapper support 1 is pivoted at 5 and rests and traverses upon a suitable traveling bed 6 which is adapted to move laterally upon a suitable support table 7. The bed 6 is provided with a suitable rack 85 8 with which engages a pinion or pinions 9 mounted upon a shaft 10, rotation of which shaft will cause the bed to be moved in one direction or the other across the support or table along the line A—A in Fig. I. A suitable stop pin 11 may be provided on the table 7 with which a lug 12 on the bed 6 is adapted to contact, the lug and pin coöperating to stop the motion of the bed in one of 90 its directions of movement.

95 For a purpose presently to be explained a clutch member 13 is rigidly attached to the shaft 10 and coöperates with a clutch member 14 carried by a sleeve 15 mounted loosely upon the shaft 10 and free to move laterally 100 thereon, and provided with one or more pulleys 16. In the present instance as the pulley 16 is turned by hand I have shown but one pulley.

105 It will be understood that the rotation of the pulley 16 will communicate motion to the bed 6 through the medium of shaft 10 and pinion 9. Any suitable means may be employed for imparting rotation to the rollers 2. In the present instance I have shown 110

a driven pulley 17 coupled with the pulley 16 by a belt 18. The shaft 19 of the driven pulley is carried by brackets 20 or otherwise suitably supported and is provided with a pinion 21 adapted to mesh with pinions 22—23—24 carried by the shafts 27—26—25 of the rollers 2. The shafts 25—26—27 are carried in the end brackets 28, which by means of a connecting bar 29 and handle 30 are secured together to constitute a frame, which frame preferably turns upon the shaft 27 as a pivotal axis. The object of turning the frame upon the shaft 27 as a pivotal axis is to cause the rollers to hug the bunch as closely as possible as they are swung into position, so as to efficiently hold the wrapper thereto and turn the same down snugly against the bunch to form the tuck.

In Figs I, II and III, I have shown the rollers as in position to effect the rolling operation and in Fig. IV I have shown the frame as swung upward to permit the bunch to be put in place on the rolling table 1.

It is believed that the operation of the parts so far described will be obvious from the description and drawings.

In order to efficiently effect the rolling of the wrapper about the bunch means should be provided whereby after the tuck has been formed the wrapper is presented diagonally to the bunch to be wrapped about the same, and means should also be provided to wrap the head. I have accomplished these objects in various ways. One construction whereby this object may be accomplished is shown in the drawings wherein the pivoted rolling table 1 is provided with a cam surface 31 substantially parallel with the direction of movement initially imparted to the table by the traveling bed upon which it rests and swings, and with a cam face 32 making such an angle with the cam face 31 as to cause the wrapper to be presented to the bunch at the proper angle. The cam faces 31—32 coöperate with the pin 33 (see Fig. III) so that as the rolling table moves forward with the bed upon which it rests and swings, the face 32 will come in contact with the pin 33 and swing the rolling table upon its pivot 5 for a purpose presently to be explained.

The operation of the construction shown in Figs. I, II, III and IV will now be described. The wrapper *b* is laid upon the rolling table in the proper position, which may either be marked out or in case a suction box is employed, defined by the apertures thereof. The bunch is put in place on the end of the wrapper and the wrapper end turned around the end of the bunch as shown in Fig. III, the rollers serving, when they are swung from the position shown in Fig. IV, which is the open position, to the other position shown in the other figures, to grip the wrapper firmly against the bunch.

The pulley 16 may now be rotated either by hand or power. The effect of this rotation will be to impart rotary means to the rollers 2 and a forward movement along the line A—A to the bed and rolling table. 70 The rolling table moves forward at such a rate of speed with respect to the rollers as to maintain the wrapper under slight tension so as to wrap it firmly about the bunch.

It will be observed by reference to Fig. 75 II that the wrapper is peeled from the rolling table rather than drawn therefrom laterally, and that the bunch bears upon the wrapper on the rolling table in such manner that the rolling table subserves the function 80 of a fourth roller. It will also be observed that the operations of hand labor are very exactly imitated. As the rolling table continues to move forward the tuck is formed and after the formation of the tuck the apex 85 *c* of the angle formed by the faces 31—32 reaches the pin 33, the pin 33 thus contacting with the faces 32, and as the rolling table continues to move forward the pin 33 co-operating with the cam faces 32 will cause 90 the wrapper support or rolling table to be swung upon its pivot 5, thereby to present the remainder of the wrapper to the bunch at a proper angle. When the rolling table has proceeded sufficiently far to wind the 95 wrapper about the bunch, until the head is reached, the head former 5^a, which is curved or beveled to match the shape of the head of the cigar being made, has arrived in position,—for instance, the dotted line position 100 shown in Fig. I. The head forming operation now takes place. For this purpose it is sometimes advisable to permit the head-former or rolling table to stop while the rollers continue their rotation. For this I 105 have shown two different constructions, whereby this purpose may be accomplished. In Figs. I, II, III, IV, it may be accomplished by moving the sleeve 15 laterally in the direction of the arrow in Fig. I, thereby 110 separating the clutch members 13—14 and permitting the shaft 10 to remain at rest, but the rotation of the rollers to be continued. The operator by dipping her finger in a little paste and holding it upon the portion of the wrapper which is to surround the head of the cigar, can paste the head at the same time that it is being formed; it being understood that the rollers coöperate with the curved face of the head-former 5^a 115 to form the head. It will be seen that as the bunch bears upon the wrapper on the rolling table the wrapper is peeled from the rolling table and not drawn off laterally therefrom, and this rolling or peeling operation in conjunction with the coöperation of the rollers or wrapping device is to be 120 clearly distinguished from the operations wherein a rolling and peeling action is not effected, but the wrapper is drawn laterally 125 130

from a wrapper support and subjected to considerable tensile strain.

In Figs. V, VI and VII I have shown means whereby the head former alone may 5 be held still and the remainder of the rolling table permitted to traverse onward. In these figures the rolling table has a separate suction box 35 sliding on guides 34 and covered by the head former 5. The head- 10 former is also provided with a finger piece or abutment 36. When the rolling table shown in Figs. V, VI and VII is used in lieu of the rolling table shown in Figs. I, II, III and IV the operation is the same as 15 that described for the construction shown in Figs. I, II, III and IV with this difference, that when the time for forming the head of the cigar has arrived the head former may be arrested and held stationary by the 20 contact of the abutment or finger piece 36 against the finger of the operator or other suitable stop, and the remaining portion of the rolling table allowed to continue its movement.

25 I am aware that it has been proposed to employ a belt or apron to coöperate with rollers in rolling cigars, the portion of the wrapper on the belt receiving the thrust of the bunch, whereby the wrapper which is 30 supported upon a wrapper support extending beyond the path of travel of the belt is drawn from the said wrapper support. I do not claim such a construction. A type of this construction is shown in Fig. 35 of 35 Patent No. 535,048 dated March 5, 1895.

The reason for maintaining the head former stationary as above described is to permit the wrapper to be wound on the bunch in a straight line, that is without the 40 spiral movement with which the wrapper is wound on the bunch during the rest of the operation. In the construction shown in Figs. I, II, III, and IV this is accomplished by stopping the entire table and in 45 the form shown in Figs. V, VI, and VII, the head former is held by the finger of the operator during the remainder of the operation.

Having described my invention what I 50 claim and desire to secure by Letters Patent is:

1. In a wrapping mechanism, the combination with a bunch receiver having the general configuration of the bunch, of means for holding the bunch against the receiver, and means for producing a movement between the receiver and the holding means to wind the wrapper about the bunch.
2. In a wrapping mechanism, the combination with a bunch receiver, of a wrapper support arranged to hold the bunch thereagainst, and means for producing a movement between the support and the receiver to wind the wrapper about the bunch.
3. In a wrapping mechanism, the combi-

nation with a wrapper support, of a receiver in which the bunch is rotated, the bunch being held between the support and the receiver during the wrapping operation, and means for giving the wrapper support a 70 movement during the wrapping operation.

4. In a wrapping mechanism, the combination with a wrapper support, of a bunch receiver having the general configuration of the bunch in which the bunch is rotated, the bunch being held between the support and the receiver during the wrapping operation, and means for giving the wrapper support a 75 movement during the wrapping operation.

5. In a wrapping mechanism, the combination with a wrapper support, of a receiver, the bunch being held against the receiver by the support, means for operating the receiver to give the bunch a rotating movement, and means for giving the support a 80 movement to deliver the wrapper.

6. In a wrapping mechanism, the combination with a wrapper support having a plane face, of a receiver in which the bunch is rotated, the bunch being held between the support and the receiver during the wrapping operation, and means for giving the wrapper support a movement during the 90 wrapping operation.

7. In a wrapping mechanism, the combination with a wrapper support having a plane face, of a bunch receiver having the general configuration of the bunch in which the bunch is rotated, the bunch being held between the support and the receiver during the wrapping operation, and means for giving the wrapper support a movement during the 95 wrapping operation.

8. In a wrapping mechanism, the combination with a wrapper support having a plane face, of a bunch receiver, the bunch being held against the receiver by the support, means for operating the receiver to give the bunch a rotating movement, and means for giving the support a movement to 100 deliver the wrapper.

9. In a wrapping mechanism, the combination with a wrapper support, of a receiver against which the bunch is held and in which it is rotated during the wrapping operation, and means for producing a relative angular movement between the support and receiver during the wrapping operation.

10. In a wrapping mechanism, the combination with a wrapper support, of a receiver against which the bunch is held and in which it is rotated during the wrapping operation, and means for producing a relative approaching movement between the support and receiver during the wrapping operation.

11. In a wrapping mechanism, the combination with a wrapper support, of a receiver against which the bunch is held and in which it is rotated during the wrapping operation, and means for giving the support 125

- an angular movement during the wrapping operation.
12. In a wrapping mechanism, the combination with a wrapper support, of a receiver 5 against which the bunch is held and in which it is rotated during the wrapping operation, and means for giving the support an approaching movement during the wrapping operation.
13. In a wrapping mechanism, the combination with a bunch receiver, of a wrapper support provided with a pressing surface located outside the line which the wrapper occupies when it is on the support, and 15 means for producing a movement between the receiver and the support.
14. In a wrapping mechanism, the combination with a bunch receiver, of a suction wrapper support provided with a pressing 20 surface lying outside the field of suction, and means for producing a movement between the receiver and the support.
15. In a wrapping mechanism, the combination with a bunch receiver, of a suction 25 wrapper support having a plane face and having a pressing surface lying outside the field of suction, and means for producing a movement between the receiver and the support.
16. In a wrapping mechanism, the combination with a suction wrapper support, of coöperating wrapping means against which the bunch is held by the wrapper support, and means for producing a relative angular 30 movement between the support and the coöperating wrapping means during the wrapping operation.
17. In a wrapping mechanism, the combination with a suction wrapper support having 40 a pressing surface located outside the field of suction, of a coöperating wrapping means against which the bunch is held by the wrapper support, and means for producing a relative movement between the support and the wrapping means during the wrapping operation.
18. In a wrapping mechanism, the combination with a suction wrapper support provided with a pressing surface lying outside 45 the field of suction, of a pair of wrapping members against which the bunch is held by the wrapper support, and means for giving the wrapper support and wrapping members movements to supply the wrapper and 50 rotate the bunch to wind the wrapper thereon.
19. In a cigar making machine the combination of wrapping devices, means for actuating the same, a rolling table adapted 60 to support the wrapper, and provided with means for holding the wrapper stationary thereon, said rolling table serving as a complemental member of the wrapping devices to effect the rolling, and being so located 65 with respect to the wrapping devices as to receive the bunch directly against the wrapper supported on said rolling table, and means for effecting relative movement between the rolling table and the wrapping devices whereby the cigar is rolled directly 70 on the table.
20. In a cigar making machine the combination of a rolling table having means for holding the wrapper stationary thereon with automatic wrapping devices, the said rolling table receiving the thrust of the bunch directly against a wrapper carried thereon, and means for effecting relative movement between the rolling table and the wrapping devices, whereby the cigar is 75 80 rolled directly on the table.
21. In a cigar making machine the combination of a set of wrapping rollers, means for rotating the same and a wrapper support or rolling table, having means for holding 85 the wrapper stationary thereon, which wrapper support or rolling table is so located with respect to the rollers that the rolling takes place on the rolling table, which thereby forms a complemental member of said rollers, and means for effecting 90 relative movement between the rolling table and the rollers.
22. The combination in a cigar making machine of a rolling table having means for 95 holding the wrapper stationary thereon with means for rolling the cigar directly on the said table, which table receives the thrust of the bunch directly against the wrapper thereon, while the wrapper is under the influence of the holding means, and means for effecting relative movement between the rolling table and the means for rolling the cigar.
23. In a cigar making machine the combination of a rolling table having means for holding the wrapper stationary thereon with a set of wrapping rollers, the said wrapping rollers and rolling table being so located with respect to each other that the 100 bunch is rolled directly in contact with a wrapper supported upon the rolling table whereby the said rolling table subserves the function of another wrapping roller and means for effecting a relative movement between the rollers and the rolling table.
24. In a cigar making machine the combination of a traveling rolling table having means for holding a wrapper stationary thereon, with a set of wrapping rollers, the said rolling table and rotating rollers co-operating with each other to wind the wrapper around the bunch, the said rolling table receiving the thrust of the bunch upon a wrapper thereon, and means for effecting 105 a relative movement between the rolling table and the wrapping rollers.
25. In a cigar making machine the combination of a rolling table, having means for holding a wrapper stationary thereon, with 110

- a set of wrapping rollers mounted above the said rolling table and in such proximity thereto as to hold the bunch firmly against the wrapper on the rolling table so as to roll the cigar directly upon the rolling table, and means for effecting relative movement between the rolling table and the wrapping rollers.
26. In a cigar making machine the combination of a rolling table provided with an element of a head-forming means, wrapping rollers adapted to roll the cigar while the same is in contact with the rolling table and head-forming element, means for producing relative movement between the rolling table and the wrapping rollers and means for maintaining the element of the head-forming means stationary during the head-forming operation.
27. The combination in a cigar making machine of a movable rolling table, provided with an element of a head forming means, wrapping devices adapted to roll the cigar directly upon the rolling table, and means for effecting relative movement between the rolling table proper and the head-forming element, so that said head-forming element may remain stationary while the rolling table continues to perform its function to facilitate the rotation of the bunch.
28. In a cigar making machine the combination of a rolling table having means for holding a wrapper stationary thereon, a series of wrapping rollers adapted to hold the cigar firmly against the said rolling table and means for imparting to said rolling table two movements in directions at angles to each other, one a pivotal movement, and the other a movement of translation.
29. In a cigar making machine the combination of a set of rollers, a rolling table having means for holding a wrapper stationary thereon, with means for imparting rotation to the said rollers and for producing relative movement between the said rollers and the rolling table, the said rolling table performing the double function of supporting the wrapper and facilitating the rotation of the bunch.
30. In a cigar making machine the combination of wrapping devices with means for actuating the same, a rolling table having means for holding a wrapper stationary thereon in a position which it maintains while the rolling is being effected, and means for bringing about a relative movement between the rolling table and the wrapping devices, the said rolling table receiving the bunch directly against the wrapper which is supported thereon and serving as a complementary rolling member.
31. In a cigar making machine the combination of a table adapted to support a wrapper and provided with means for holding said wrapper stationary thereon, wrapping devices adapted to engage a bunch, the bunch being held in contact with the wrapper on the table, means for producing a relative movement between the rolling table and the wrapping devices whereby the bunch is rolled over the wrapper, and means for actuating the wrapping devices to effect the wrapping.
